UNITED STATES PATENT OFFICE.

WILLIAM ORIN ALDRICH, OF WHITINSVILLE, MASSACHUSETTS, ASSIGNOR
TO THE WHITIN MACHINE WORKS, INCORPORATED, OF WHITINSVILLE,
MASSACHUSETTS.

GUIDE-EYE FOR SPINNING-FRAMES.

SPECIFICATION forming part of Letters Patent No. 740,611, dated October 6, 1903.

Application filed February 5, 1903. Serial No. 142,008. (No model.)

To all whom it may concern:

Be it known that I, WILLIAM ORIN ALDRICH, a citizen of the United States, residing at Whitinsville, in the county of Worcester and State of Massachusetts, have invented a new and useful Improvement in Guide-Eyes for Spinning-Frames, of which the following is a specification.

This invention has reference to an improvement in guide-eyes for spinning-frames, and more particularly to improvements in mechanism for adjustably securing guide-eyes to the finger-boards of spinning-frames or similar machines.

15 In adjustable guide-eyes for spinning-frames or similar machines it is desirable to accurately adjust the guide-eye over the center of the spindle and to firmly secure the guide-eye to the finger-board after adjustment by the operator.

20 The objects of this invention are to simplify the construction and the operation of adjustably securing guide-eyes to the finger-boards of spinning-frames or similar machines; and 25 the invention consists in the peculiar and novel construction of the guide-eye and a clamping mechanism in the finger-board to adjustably secure the guide-eye to the finger-board, as will be more fully set forth herein- 30 after.

Figure 1 is a plan view looking at the under side of a finger-board, showing my improved guide-eye and clamping mechanism for adjustably securing the guide-eye to the 35 finger-board. Fig. 2 is a sectional view through the finger-board, with the guide-eye and clamping mechanism shown in full lines; and Fig. 3 is an enlarged cross-sectional view through the finger-board, guide-eye stem, and 40 clamping mechanism.

In the drawings, *a* represents the hinged finger-board of a spinning-frame having the circular aperture *a'* in the under side of the clamping mechanism and the off-center intersecting duct *a''* for the guide-eye stem. The 45 guide-eye *b* has the usual eye *b'* and the stem *b''*, with the flattened portion *b''* on its upper surface. The clamping mechanism in the aperture *a'* consists of the circular clamping 50 nut *c*, having the flat surface *c'*, the projecting boss *c''*, and the two fins *c'' c''* to engage

with or be forced into the wall of the aperture *a'* in the wooden finger-board *a*. The circular clamping-head *c'*, with the countersunk central opening *c''* for the clamping-screw *c''* in screw-thread engagement with the clamping-nut *c*, secures the stem *b''* of the guide-eye between the clamping-nut *c* and the clamping-head *c'*, as shown in Fig. 3. The projecting boss *c''* acts as a fulcrum for the clamping-head *c'*, and the flattened portion *b''* on the guide-eye stem, in connection with the flat surface *c'* on the clamping-nut *c*, prevents the guide-eye from turning when secured in the clamping mechanism. 55

In assembling the parts of my improved guide-eye the clamping-nut *c* with the fins *c'' c''* on its edge is forced into the circular aperture *a'* in the wooden finger-board, forcing the fins *c'' c''* into the wood to prevent turning 60 of the nut and to rigidly secure the stem of the guide-eye. The stem of the guide-eye is now pushed into the duct *a''* and over the clamping-nut, bringing the flattened portion of the stem and the flat surface of the clamping-nut into engagement. The clamping-head *c'* is now placed in the aperture *a'* and secured in position by the clamping-screw *c''*. 65

In adjusting my improved guide-eye the operator loosens the clamping-screw *c''*. The 70 guide-eye may now be accurately adjusted over the spindle and firmly secured in its adjusted position by tightening the clamping-screw. 75

Having thus described my invention, I 80 claim as new and desire to secure by Letters Patent—

1. In a guide-eye, a hinged finger-board, there being an aperture in the finger-board with an off-center intersecting duct for the 85 guide-eye stem, a two-part clamp in the aperture engaging with the guide-eye stem, and a screw in screw-thread engagement with the clamp to operate the clamp and adjustably secure the guide-eye to the finger-board, as 90 described.

2. In a guide-eye, the combination with the hinged finger-board *a* having the circular aperture *a'* and the off-center intersecting duct *a''*, the guide-eye *b* having the eye *b'* and the 95 stem *b''* with the flattened portion *b''*, the circular clamping-nut *c* having the flat surface 100

c' , the projecting boss c^2 , and the fins c^3 c^3 , and the circular clamping-head c^4 with the countersunk central opening c^5 for the clamping-screw c^6 in screw-thread engagement with the clamping-nut c , all for the purpose as described.

In testimony whereof I have signed my

name to this specification in the presence of two subscribing witnesses.

WILLIAM ORIN ALDRICH.
